JUICER OR SIMILAR ARTICLE

Charles O. Bliss, P.O. Box 47607, Los Angeles, Calif.

Filed Nov. 13, 1964, Ser. No. 82,593

Term of patent 14 years

(Cl. D89—1)

FIG. 1

FIG. 2

FIG. 3

FIG. 5

FIG. 4

FIG. 1 is a top plan view of juicer showing my new design;

FIG. 2 is a side elevational view thereof;

FIG. 3 is a bottom plan view thereof;

FIG. 4 is an end view as seen from the right of FIG. 2; and

FIG. 5 is an enlarged fragmentary sectional view on the line 5—5 of FIG. 1.

I claim:

The ornamental design for a juicer or similar article, substantially as shown.
